POCKET PERFUME ATOMIZER

Leopold K. Kuhnl, Stratford, Conn.

Application February 12, 1948, Serial No. 7,781

3 Claims. (Cl. 132—79)

1

This invention relates to a pocket perfume atomizer, and has for an object to provide an improved and simplified construction for this type of device which will be reliable and effective in operation and not likely to get out of order.

Another object is to provide a construction which will simplify the operation of the device.

A further object is to provide with the operating mechanism of the atomizer a cosmetic holder for such materials as lipstick and the like.

With the foregoing and other objects in view, I have devised the construction illustrated in the accompanying drawing forming a part of this specification. It is, however, to be understood the invention is not limited to the specific details of construction and arrangement shown, but may embody various changes and modifications within the scope of the invention.

In this drawing:

Fig. 1 is a longitudinal section of the device on an enlarged scale and showing it closed for carrying in the pocket or handbag;

Fig. 2 is a top plan view thereof;

Fig. 3 is a bottom end view;

Fig. 4 is a side elevation of the top, showing the device open and ready for use;

Fig. 5 is a top plan view of the body with the closure removed, and

Fig. 6 is a longitudinal section of the combined operating means for the plunger and cosmetic holder, showing it removed from the device for use.

The device comprises a body 10 formed of a solid integral block bored from the top or upper end to form a piston cylinder or chamber 11, and bored from the bottom or lower end to form a liquid chamber 12. Thus the two chambers in the block are separated by an integral dividing wall 13 in which is formed an air passage 14 by drilling longitudinally from the bottom or lower end of the body and stopping short of the top wall, as indicated in Fig. 1. After this passage is drilled a larger opening 15 is drilled from the lower end to a short distance above the bottom of the chamber 11, which breaks through the connecting wall between the air passage 14 and the air cylinder 11, forming a connecting air passage 16. The bottom portion of this drilled opening 15 is then closed by a plug 17 shorter than the drill-in so as to leave the passage 16. The plug may be a tight drive fit to retain it in the opening, or it could be secured by some other means, such, for example, as soldering or threading, if preferred.

2

Mounted in the air cylinder 11 is a pump piston or plunger 18, similar to an air pump piston, operated by a hand knob 19 and under which is a spring 20 tending to shift it to its upper position against a stationary stop to limit its upward movement. In the present construction this stop comprises a pin 21 mounted in a side wall of the cylinder and projecting at its inner end into a longitudinal channel or groove 22 formed in the outer wall of the piston and terminating at its lower end is a stop shoulder 23 positioned to engage the pin 21 to limit upward movement of the piston. The coaction of the pin and groove also retains the piston against turning movement. Secured to the lower end of the piston is any usual type of cupped flexible packing 24 of rubber or leather which operates in the usual manner to permit air to flow by it into the lower portion of the cylinder when the piston moves upwardly, but the side walls of which are forced laterally against the side walls of the cylinder by pressure of air as it is compressed by downward movement of the piston to hold the air pressure. The piston is of somewhat smaller diameter than the cylinder chamber to permit this air to flow past the piston, and this action may also, if desired, be facilitated by an air inlet opening 25. The operating knob or top 19 is substantially within the cylinder when in the lower position, so the top surface of this knob is substantially even or flush with the top surface 44 of the body, and does not project materially above this surface to catch on other articles.

The chamber 12 forms a supply reservoir for liquid perfume, and its lower end is closed by a closure plug 26 threaded into the lower end of the opening, and it has an enlarged head forming a shoulder 27 cooperating with a sealing washer 28 to make a tight closure. This is also used as a filling opening, the plug being provided with some means for turning it to remove it or tighten it up, such, for example, as a curved slot 29 adapted to receive a coin for operating the closure.

Mounted in the top wall of this reservoir is a capillary tube 30 extending downwardly nearly to the bottom of the chamber 12 and open at its lower end. At its upper end above the top wall 31 it terminates in a cone-shaped nipple 32 having a fine discharge opening 33, and the top of this nipple is on substantially the same level as the top surface 34 of a raised portion of the top wall 31. From the upper end of the air passage 14 there is drilled a lateral air discharge passage

25, somewhat upwardly and outwardly inclined, and which leads to a point at the side of and in alignment with the top of the nipple 32. If preferred, a second nipple 36 may be mounted in the upper end of this passage, having a fine discharge opening 37 directed across the top of the nipple 32 and the liquid discharge passage 33. Also provided in the top wall 34 is an air inlet or breather passage 38 leading from the top surface 34 to the reservoir or chamber 12 for entrance of air to permit discharge of liquid from the chamber.

The projecting ends of the nipples 32 and 37 are enclosed by a cover or closure 39 hinged to the body at 40 and carrying a gasket or packing 41 to seat on top of the nipple 32 and top wall 34 when the closure is closed, as shown in Fig. 1, to seal this nipple and air passage so that there will be no leakage from the device when it is being carried, or at any other time when not in use. The top wall or upper end of the body comprises laterally spaced stepped portions 44a extending into notches or recesses 39a extending forwardly from the rear edge of the closure. The upper end of the body is recessed at 40a to receive the side portions 39b of the closure. This closure at its free end is shaped to correspond to the shape of the side wall 42 of the body, and also its top wall or surface 43 is even with the highest part 44 of the top wall of the body, so that when the closure is closed the device will have a smooth outer surface. A spring 45 on the hinge pin 40 tends to swing the closure 39 to an upright or open position, as shown in Fig. 4, and at its inner end the closure has a projecting shoulder 46 adapted when the piston 18 is in its inner or lower position to seat on a shoulder 47 provided on this piston. In this position, as the spring 20 tends to force the piston 18 upwardly or outwardly, it forces the shoulder 47 against the under side of the projection or the shoulder 46 and holds the closure 39 tightly closed with the packing 41 pressed tightly over the passage 33 in the nipple 32 and the air passage 38 to seal them. These shoulders 46 and 47 are located well below or inwardly of the top wall 44 of the body so they are well covered and protected and will not catch on other objects.

To open the closure all that is necessary is to push downwardly a short distance on the knob 19. This carries the shoulder 47 downwardly a sufficient distance to release the shoulder 46 on the closure and permit the spring 45 to swing the closure to the upright or open position of Fig. 4. This also releases the piston 18 and the knob 19 so that they are shifted to their upper positions by the spring 20. Now, to use the device as an atomizer, the operator gives a quick push downwardly on the knob 19 which causes the piston 18 to force air through the passage 14 and out the discharge passage 37 across the top of the nozzle passage 33 to act as an atomizer and produce a very fine spray of liquid from the reservoir 12 which has been carried practically to this nozzle 32 by the capillary tube 30. This will produce a fine spray of liquid or perfume for application to any location desired. Ordinarily the device is designed so that one depression of the plunger or piston will spray about one drop of perfume for each application. In closing the device the plunger or piston is depressed sufficiently to permit the shoulder 46 on the closure to swing over the shoulder 47 on the plunger. The closure is then swung downwardly to the closed position of Fig. 1 and the plunger released.

Also combined with the plunger or piston 18 is a cosmetic carrier and applicator for cosmetics, such, for example, as lipstick or the like. For this purpose the plunger or piston 18 is made hollow or bored from its outer end to form a chamber 48 to receive a tubular holder or shell 49 open at its lower end 50, and secured to which and mounted thereon at its upper end is the operating knob 19 for the plunger or piston 18. This knob also functions as a grip or holder for the device 49 in which is mounted a slidable carrier 51 for the stick of cosmetic 52, such, for example, as lipstick. This carrier has a lateral projection or lug 53 projecting through a longitudinal slot 54 in the side of the shell 49, this slot terminating at 55 at its lower end spaced inwardly from the lower end of the shell to form a stop to limit outward movement of the carrier 51 and the plastic stick 52. Upward or inward movement may be limited by the upper end of the slot or by the stem 56 of the knob or grip 19. The upper portion of the plunger or piston is provided with a shoulder 57, so that when the shell 49 is inserted in the plunger the lug 53 will seat on this shoulder 57 and retract the plastic stick 52 into the shell 49 by inward movement of the shell, as shown in Fig. 1, so that there will be no danger of jamming the lower end of this plastic stick against the bottom of the chamber 48. After removal of the casing 49 from the plunger the free end of the plastic stick may be projected through the open end 50 of the shell by the operator gripping projecting lug 53 and pushing it downwardly, but this lug also acts as described to automatically retract the plastic stick into the shell when the shell is inserted in the chamber 48 in the plunger or piston. This shell has a fairly tight sliding fit in the plunger so that it will not inadvertently drop out, but is withdrawn for use by pulling outwardly on the knob 19. Or, if preferred, a suitable catch or other securing means (not shown) may be employed to retain it in the plunger. If the plastic or lipstick is removed the chamber 48 in the plunger may be used as a container for safety-pins, hair-pins or various other articles.

It will be seen that this construction is a very simple and effective one and one that will not be easily gotten out of order. By employing a solid integral block for the body, possibility of leakage is reduced to a minimum and the application of the cosmetic or lipstick holder to the plunger makes use of space that would otherwise not be utilized, and the cosmetic holder structure is employed as the operating means for the plunger of the atomizer. Also, the structure is such that in inserting the plunger operating means to the operative position the plastic stick is automatically retracted to a position where it is protected against crushing or smearing other elements of the device. Also, with this construction the operating knob for the atomizer functions also as the hand grip or holding means for the plastic stick when used for applying this material, but if not desired to provide the cosmetic the piston can be made solid to simplify manufacture. The body may be of any suitable material, such for example as metal, including aluminum, alloys and so forth, or glass, plastics or other transparent materials.

Having thus set forth the nature of my invention, I claim:

1. An atomizer comprising a body provided with a chamber for liquid and a laterally spaced cylinder opening through its top wall, a discharge nozzle leading from said chamber, an air pas-

sage leading from the cylinder to a position adjacent the discharge nozzle, a plunger in the cylinder forming a piston, said plunger being provided with a chamber opening through its outer end, a removable holder in said plunger chamber comprising a shell open at its inner end and provided with a longitudinal slot in its side wall, a carrier slideable in the shell and provided with a projection extending outwardly through said slot, a knob secured to the shell forming an operating means for the piston and a hand grip for removing the holder from the plunger, and said piston being provided with a shoulder in alignment with the projection and arranged to cooperate with it to retract the carrier into the shell as the shell is inserted in the piston.

2. A liquid atomizer comprising a body including a chamber for liquid and a cylinder, a discharge nozzle connected with the chamber, an air passage leading from the cylinder to a position adjacent said nozzle, a plunger in the cylinder forming a piston, said plunger being provided with a chamber opening through its outer end, a holder in said plunger chamber and removable through said open end, said holder comprising a shell open at its inner end and provided with a longitudinal slot in its side wall, a carrier slideable in the shell provided with a lug extending through the slot to form a hand grip for shifting the carrier, a hand knob secured on the outer end of the shell forming an operating means for the piston and a handle for removing the holder, and a shoulder on the plunger positioned to cooperate with the lug to retract the carrier into the shell as the shell is inserted in the plunger.

3. An atomizer comprising a body provided with a chamber for a liquid, a discharge nozzle leading from said chamber to the top of the body,

a cover pivoted to the body and normally adapted to close said nozzle, resilient means tending to move the cover to uncover the nozzle, said body being also provided with a chamber opening 5 through its upper end forming a cylinder, a pressure piston mounted in the cylinder and provided with an operating head at its outer end located in and substantially filling the entrance to the cylinder when in its inner position, means tending to shift the piston upwardly out the top of the body, said body being provided with an air passage leading from the cylinder to a discharge position adjacent the nozzle, cooperating shoulders on the piston and cover located below and independent of said head to hold the cover in closed position and the piston in its inner position, and said shoulders being so arranged as to release the cover by limited inward movement of the piston only.
